UNITED STATES PATENT OFFICE

ALBERT R. LAWSON, OF HAMILTON, ONTARIO, CANADA, ASSIGNOR TO TORONTO TYPE FOUNDRY COMPANY, LIMITED, OF TORONTO, CANADA

MANIFOLDING SALES BOOK

Application filed June 3, 1932. Serial No. 615,094.

This invention relates to triplicate manifolding books, that is books in which two copies of an original record are required, one of which may be left in the book if desired, and my object is to provide a simple and practicable manifolding book of the above type which can be cheaply manufactured.

A further object is to so construct the book that the carbon leaves may be manipulated and temporarily disposed of without danger of soiling the hands or merchandise by contact with the carbonized surfaces.

A further object is to so arrange the book that one or more used carbon leaves may be removed at any time desired.

I attain my objects by means of a construction which may be briefly described as follows: The book is formed of a plurality of manifolding units, each manifolding unit comprising a sheet of paper folded on itself to form an original record leaf and a duplicate record leaf; and a second sheet provided with a stub and folded on itself to form two leaves, normally enclosed by the first mentioned leaves, the lower leaf of the second sheet being carbonized on its under surface only and the upper leaf also carbonized on its under surface. The stubs are bound to a cover, which is provided with a front cover leaf and a protective cover leaf for used carbon leaves hinged to the free end of the front cover leaf.

The invention is illustrated in the accompanying drawings in which

Fig. 1 is a perspective view of a sheet forming the original and duplicate record leaves;

Fig. 2 a perspective view of a sheet forming the transfer leaves and triplicate;

Fig. 3 a perspective view of the book cover;

Fig. 4 a perspective view of a complete book ready for use;

Fig. 5 a perspective view of the book illustrating the method of handling the carbon leaves after use;

Fig. 6 a perspective view illustrating the position of the parts of the book when carbon leaves are to be torn out; and

Fig. 7 a perspective view of a modification of the arrangement of the record leaves and transfer leaves.

In the drawings like numerals of reference indicate corresponding parts in the different figures.

Referring to Fig. 1, there is shown therein a sheet of paper folded to form the original record leaf 1, the duplicate record leaf 2 and the stub 3 at the free end of the duplicate record leaf. Lines of weakness 4 and 5 are preferably formed between the parts.

In Fig. 2 is shown a sheet of thin paper folded to form a carbon leaf 6, a carbon record leaf 7 and a stub 8. Lines of weakness 9 and 10 are preferably formed between the parts.

The leaves 6 and 7 are carbonized on their under sides, but it is essential that the back of the leaf 7 be not carbonized as this sheet not only serves to transfer to the under duplicate record leaf a copy of the original, but also serves itself as a record leaf, a copy of the original being transferred to its back by the carbon leaf 6.

Each leaf 6 is formed with an uncarbonized margin 15 at its free end and each leaf 7 with a similar margin 16 adjacent the carbonized part.

The cover is shown in Fig. 3 and may be made either integral or in one or more parts secured together. The cover comprises the back 11 on which hinges the stop leaf 12 employed in the usual way to prevent records made on one manifolding unit being impressed on an underlying unit, the front cover leaf 13 and the protective leaf 14 hinging on the free end of the front cover leaf. The stubs 3 and 8 of a plurality of the manifolding units are bound into the back of the cover in a known manner.

Assuming one manifolding unit to have been previously used, the book will appear as shown in Fig. 4 with the uppermost leaves 1 and 2 embracing a set of leaves 6 and 7 and a set of leaves 6 and 7 held between the cover leaves 13 and 14. A transaction may then be recorded on the exposed leaf record 1 and transferred to the back of

the underlying leaf 7 and the face of the leaf 2.

- After the recording of a transaction is completed the book may be manipulated as follows to prepare it for the recording of a new transaction. Grasp the upper left hand corners of the leaves 1 and 6 between the thumb and first finger of the left hand, at the same time grasping the lower right hand corner of the protective leaf 14. Raise the leaves 1 and 6 and bring forward the leaf 14 till the leaves 6 and 7 underlying it are brought forward and dropped on the leaf 7 exposed by raising the leaves 1 and 6.
- See Fig. 5. The leaf 6 grasped by the left hand is then dropped over leaves 6 and 7 brought forward by the protective leaf, while a hold on the leaf 1 is maintained. Then by carrying the leaf 1 backward and upward the two sets of leaves 6 and 7, one embracing the other, may be turned back on the cover leaf 13 and the protective leaf 14 dropped over them. The original and duplicate may then be torn out and the stop sheet 10 turned in under a fresh manifolding unit to prepare the book for use in recording a fresh transaction. At any time one or more used carbon leaves may be drawn out to the position shown in Fig. 6 and the leaves 6 torn off leaving the record transfer leaves 7 in the book to serve as triplicate records.

As the leaves 7 may be numbered to correspond with the other record sheets of the unit to which they belong, they serve as a bound reference of recorded transactions.

The book might also be operated from back to front, in which case the record leaves would be correspondingly numbered from back to front.

It is also possible to paste the stubs 8 of the transfer leaves 7 to the stubs 3 of the record leaves 2 instead of binding them directly into the book, and these stubs may be numbered (see Fig. 7).

It will be seen from the above description that a manifolding book constructed in accordance with my invention is simple, easily operated and clean to handle, since it is not necessary at any time to touch the carbonized surfaces and the carbon sheets are not exposed when the book is in use or lying on the desk in open position. The uncarbonized margins 15 of the leaves 6 enable these sheets to be handled as may be necessary without danger of soiling the fingers.

It will be understood, of course, that manifolding units constructed as described may be used in various ways and are not necessarily bound to a cover or otherwise connected, but may be merely superimposed for use in any known manner.

What I claim as my invention is:

1. In a manifolding book a manifolding unit comprising a sheet of paper provided

with a stub and folded on itself to form an original record leaf and a duplicate record leaf; and a second sheet provided with a stub at one end and folded on itself to form two leaves normally enclosed by the first-mentioned leaves, the stubless leaf overlying the other, the lower leaf of the second sheet being carbonized on its under surface only and the upper leaf also carbonized on its under surface, whereby the upper carbon leaf transfers a copy of the original to the back of the lower carbon leaf and the latter transfers a copy to the lowermost record leaf.

2. A manifolding book comprising a plurality of manifolding units each comprising a sheet of paper provided with a stub and folded on itself to form an original record leaf and a duplicate record leaf; a second sheet provided with a stub at one end and folded on itself to form two leaves normally enclosed by the first-mentioned leaves, the stubless leaf overlying the other, the lower leaf of the second sheet being carbonized on its under surface only and the upper leaf also carbonized on its under surface, whereby the upper carbon leaf transfers a copy of the original to the back of the lower carbon leaf and the latter transfers a copy to the lowermost record leaf; and a cover to which the stubs are bound formed with a front cover leaf and a protective cover leaf for used carbon leaves hinged to the free end of the front cover leaf.

3. A manifold book comprising a plurality of manifolding units each comprising connected original and duplicate record leaves normally overlying one another, and a stub connected to the other end of the lower record leaf; connected leaves normally overlying one another and enclosed by the first-mentioned leaves, the lower leaf of the second set being carbonized on its under surface only and the upper leaf also carbonized on its under surface, whereby the upper carbon leaf transfers a copy of the original to the back of the lower carbon leaf and the latter transfers a copy to the lowermost record leaf; and a stub on the lower carbon leaf adhered to the stub of a lower record leaf.

Signed at Toronto, Canada, this 30th day of May 1932.

ALBERT R. LAWSON.
